WARREN FRASIER, OF PHILADELPHIA, PENNSYLVANIA, ASSIGNOR TO UNITED SHOE MACHINERY COMPANY, OF PATERSON, NEW JERSEY, A CORPORATION OF NEW JERSEY.

HEEL-BREASTING MACHINE.

1,068,423.

Specification of Letters Patent.

Patented July 29, 1913.

Application filed October 20, 1908, Serial No. 458,630. Renewed July 17, 1912. Serial No. 710,059.

To all whom it may concern:

Be it known that I, WARREN FRASIER, a citizen of the United States, residing at Philadelphia, in the county of Philadelphia and State of Pennsylvania, have invented certain Improvements in Heel-Breasting Machines, of which the following description, in connection with the accompanying drawings, is a specification, like reference 10 characters on the drawings indicating like parts in the several figures.

This invention relates to heel breasting machines and is herein shown embodied in a machine which is intended to breast heels 15 after they have been attached to boots or shoes.

The object of the invention is to provide a machine which is adapted to breast heels quickly and accurately without danger of 20 cutting the soles of the boots or shoes.

With this object in view, the present invention in one aspect contemplates the provision in a heel breasting machine of a reciprocating breeding knife arranged to be 25 driven the same distance at each stroke and mechanism for clamping a shoe in working position with its heel so arranged in the path of the breeding knife that the latter will properly breast the heel but will not cut into 30 the shank of the boot or shoe. In the preferred embodiment of the invention there is provided a support for sustaining a shoe with its heel in the path of the breeding knife which is arranged for movement in the 35 line of movement of the knife to bring the shoe into operative relation with said knife. A stop arranged to be engaged by the tread surface of the heel serves to limit movement of the shoe toward the knife and position the 40 shoe with its shank just beyond the range of the knife so that the heel may be breasted without cutting the shank of the shoe. With this arrangement the shoe may be firmly clamped between the shoe support 45 and the stop and in proper relation to the breeding knife before the latter is actuated to breast the heel, which is advantageous in that it insures that the heel will be more accurately breasted than would be the case if 50 the shoe were loosely sustained upon a jack or shoe support in the breeding operation. The stop which is engaged by the tread surface of the heel is preferably arranged for adjustment in a direction substantially 55 parallel with the line of movement of the

knife in order that shoes having heels of different heights may be clamped in working position with their shanks just beyond the range of the knife. Preferably also there is provided means for visually indicating the 60 proper adjustments of the stop to respectively suit the standard heights of heels employed in the manufacture of boots and shoes.

The invention further contemplates the 65 provision of means for moving the shoe support in the line of movement of the knife which is so constructed and arranged that while the operator may readily effect any desired movement of the shoe support the 70 latter will remain in any of its positions and is adapted to rigidly resist the thrust of the knife in the breeding operation.

The invention further includes novel combinations of parts for supporting, positioning and holding the shoe comprising a support movable toward and from position under the knife and toward and from the knife in a vertical direction, means for clamping the shoe and means for arresting its movement toward the knife. Preferably, and as shown, the clamping and positioning means comprises a heel engaging member mounted yieldingly for movement with and by the shoe when raised toward the knife and a 85 rigid adjustable stop whereby movement of the shoe toward the knife is limited.

Other features of the invention will be hereinafter described in the specification and pointed out in the claims.

In the drawings,—Figure 1 is a side elevation of a machine embodying the present invention; Fig. 2 is a rear view of a portion of the machine shown in Fig. 1; Fig. 3 is a detail view of the last post; Fig. 4 is a view 95 in front elevation, with parts broken away, of the machine shown in Fig. 1; Fig. 5 is a detail view showing the means for limiting the upward movement of the stop.

Referring to the drawings a driving shaft 100 2 is mounted on the frame 4 and provided at one end with a driving pulley 6 adapted to be operatively connected to said shaft to impart a rotary movement thereto.

A knife carrier 8, reciprocating vertically 105 in guideways 9, is arranged to be driven the same distance at each stroke. A convenient mechanism for transmitting motion to the knife carrier comprises a crank 10 on one end of the shaft and a link 12 connecting 110

said crank to said carrier. A spring 14 having its upper end attached to the frame 4 and its lower end to the carrier 8 may serve to counterbalance the weight of the carrier. A knife 16 is adjustably clamped in a laterally projecting portion of the carrier 8 by the set screws 18. The upper end of the knife bears against the screws 20 which are threaded through a block 22 rigidly secured to or integral with the carrier 8.

A post 24, adapted to sustain a shoe support, is pivoted about a horizontal axis at 26 and arranged for limited swinging movement about said pivot, the extent of movement being determined by the play of the projection 28 in the depression 30. The post 24 carries a vertically adjustable rod 32 provided with arms 34 and 36 carrying respectively a pin 38 to enter the opening in the heel of a last and a toe rest 40 for sustaining the toe of a last. With this construction it will be seen that the shoe support is adapted to have a swinging movement about the pivot 26 between an outer inclined position in which it may receive a shoe and an inner position in which it may sustain said shoe with its heel properly located in the path of the breasting knife. The rod 32 telescopes within the post 24 and is splined therein as by means of a longitudinal slot 41 in the rod and a plate 43 extending into said slot and secured in the top of the post. A pinion 42 is supported upon the top of the post 24 and has threaded engagement with the rod 32 so that rotation of the pinion will effect longitudinal movement of the rod. Upward movement of the pinion 42 is restrained by means of fingers 44 secured to the post and provided with projections extending into a peripheral groove 46 formed in the hub of the pinion. A segmental rack 48 meshes with the pinion and is rigidly secured to a hand lever 50 pivoted to the post at 52 so that by moving said lever the operator may actuate the pinion and raise or lower the shoe support. A stop, herein shown as a flat plate 54, is arranged to be engaged by the tread surface of the heel to limit movement of the shoe toward the breasting knife. The plate 54 is arranged for vertical adjustment in order that shoes provided with heels of different heights may be positioned in proper relation with the breasting knife. A holder 56 is mounted in guideways in the frame 4 and the plate 54 is pivoted on said holder to permit it to be adjusted to bring it in parallelism with the face of the work. A set screw 60 serves to hold said plate from movement on the holder away from the work and a spring 59 may be employed to hold said plate against the set screw.

65 In the machine shown upon the drawings

the holder 56 is adapted to be moved into its different adjustments by a treadle 58. The connection shown between the treadle and the holder comprises a rod 61 adjustably connected to a lever 62 which is connected to the holder by a device to be presently described. A spring 64 tends to hold the treadle 58 in a raised position. The connection between the rod 61 and lever 62 is adapted to permit a yielding pressure 75 to be applied to the holder to move it downwardly. That shown comprises a sleeve 66 loosely mounted on the rod 61, a collar 68 connected to the lever 62 and adapted to be clamped on the sleeve 66, a spring-pressed washer 70 on the rod 61 and bearing on the sleeve 66 and a nut 72 threaded on the rod 61 below the sleeve. With this arrangement it will be seen that the spring 64 tends to move the holder 56 to its highest position. The connection between the lever 62 and holder 56 is preferably such as to permit the holder to be moved manually away from the work support when desired. It may comprise toggle arms 74, one of which is provided with a handle 76, gravity tending to hold said toggle in closed position. The breaking movement of the toggle will obviously cause the holder to be moved away from the work support.

In order to secure the plate 54 in its different adjustments to correspond with heels of different heights, adjustable means are provided to limit the upward movement of the holder. In the construction herein shown a triangular recess formed in the frame of the machine opposite the holder and opening downwardly is provided with a series of horizontal shoulders 78 arranged at equal intervals along its oppositely inclined sides. An equal number of openings 80 are formed in the holder 56, each of which is in alignment with one of the shoulders 78 so that a pin 82, if inserted in any one of the openings, is adapted to engage the corresponding shoulder and limit the upward movement of the plate 54. The openings 80 in the holder are so positioned with relation to the shoulders 78 as to sustain the pin in the positions respectively corresponding with those required for the heights of the standard sizes of heels that are commonly employed in the manufacture of boots and shoes. Graduations to indicate the proper openings for the pin for different heights of heels are respectively arranged on the frame of the machine opposite the corresponding shoulders for said openings, as shown in Fig. 5.

Mechanism to start and automatically stop the rotation of the main shaft so that the crank is rotated through one revolution and the knife carrier is moved down and then up is arranged to be controlled by the treadle 58. Any suitable mechanism adapt-

ed to impart a single rotation to the main shaft may be employed and as the same is well-known in this art it is not particularly described in this application.

5 Preliminary to the use of the machine, the operator depresses the treadle so that the holder is lowered a sufficient distance to enable the pin 82 to be inserted in the proper opening to correspond with the 10 height of heel to be breasted. Upon the release of the treadle the holder moves upwardly until the pin strikes the shoulder which is in alinement with the opening that has been selected, when the upward movement 15 of the holder is arrested. The plate 54 carried by the holder is now suitably located to position the shoe which is to be operated upon in proper relation to the breasting knife so that the heel will be 20 breasted without cutting the shank of the shoe.

In the use of the machine shown, the last which carries the shoe is placed upon the shoe support when the latter is in its outer 25 inclined position. The shoe support is then swung inwardly to position the heel of the shoe in the path of the breasting knife and the shoe is raised by means of the lever 50 so that the tread of the heel strikes the 30 plate 54 and said heel is firmly clamped between said plate and the last. The treadle is then depressed to start the machine, it being understood that the yielding connection between the rod 61 and lever 62 permits 35 this movement of the treadle even though the plate 54 remains stationary, whereupon the shaft 2 rotates through one revolution and actuates the knife to breast the heel. As the position of the plate 54 has 40 been adjusted to position the shoe with its shank just beyond the range of the breasting knife, it will be seen that the heel will be breasted without cutting the shank of the shoe. Upon the completion of the 45 breasting operation, the lever 50 is again actuated to unclamp the shoe when the latter may be removed in the usual way, leaving the machine in condition to receive another shoe.

50 By employing a stop arranged to be engaged by the tread surface of the heel to limit movement of the shoe toward the breasting knife and position the shoe in suitable relation with said knife, it will be 55 seen that variations in the heights of the different lasts employed to support the shoes does not prevent the shoes from being properly positioned with relation to the breasting knife as might otherwise be the 60 case.

It will be seen that in the machine described although movement may be easily imparted to the shoe support by the hand lever 50 to bring a shoe into and out of 65 operative relation with the knife the fact

that this movement is transmitted through a pinion which has threaded engagement with the supporting rod of the shoe support obviates any liability of the shoe support yielding to the thrust of the knife in 70 the breasting operation.

The novel work support, herein described but not claimed, is covered by a divisional application, Serial No. 531,798, filed December 7, 1909.

Having described my invention, what I claim as new and desire to secure by Letters Patent of the United States is:

1. A heel breasting machine, having in combination, a reciprocating breasting knife 80 arranged to be driven the same distance at each stroke, a support for sustaining a shoe with its heel in the path of the breasting knife arranged for adjustment to bring the shoe into operative relation to the knife, 85 limiting means, and means comprising a presser plate arranged for movement toward the tread surface of the heel and for reverse movement against the limiting means to positively limit movement of the 90 shoe toward the knife.

2. In a machine of the class described, the combination with a breasting knife arranged to be driven the same distance at each stroke, of a clamping member arranged to limit movement of a shoe toward the knife by engagement with the tread surface of its heel, a shoe support and means comprising inclined engaging surfaces for moving said support longitudinally of the knife constructed to clamp the shoe positively by wedging pressure with the tread surface of its heel in engagement with the clamping member.

3. A heel breasting machine, having in combination, a reciprocating breasting knife arranged to be driven the same distance at each stroke, a support for sustaining a shoe with its heel in the path of the breasting knife arranged for movement 105 manually in the line of motion of the knife, and a stop constructed for adjustment to definite distances from the limit of movement of the knife and arranged to be engaged by the tread surface of the heel to 110 limit movement of the shoe toward the knife, the said stop being stationary during the cutting stroke of the knife.

4. A heel breasting machine, having in combination, a reciprocating breasting knife, having a constant stroke, a support for sustaining a shoe with its heel in the path of the breasting knife arranged for adjustment to bring the shoe into operative relation with the knife, means for limiting the movement of the shoe toward the knife comprising a stop arranged to be engaged by the tread surface of the heel, and means for sustaining said stop in a predetermined 120 relation to the limit of movement of the 125 shoe.

65 operative relation with the knife the fact

knife constructed to permit such relation to be varied by adjustment of the stop to suit heels of different heights.

5. A heel breasting machine, having in combination, a breasting knife having a constant stroke, a support for sustaining a shoe with its heel in the path of the knife arranged for adjustment to bring the shoe into operative relation with the knife, means for limiting movement of the shoe toward the knife comprising a stop arranged to be engaged by the tread surface of the heel and mounted for adjustment in a direction substantially parallel with the line of movement of the knife, yielding means tending to move the stop away from the shoe support, means including a treadle for moving the stop in the opposite direction and adjustable means for positively limiting movement of the stop away from said shoe support.

6. A heel breasting machine, having in combination, a reciprocating breasting knife arranged to be driven the same distance at each stroke, a support for sustaining a shoe with its heel in the path of the breasting knife arranged for adjustment to bring the shoe into operative relation with the knife, a stop arranged to be engaged by the tread surface of the heel to limit movement of the shoe toward the knife and means for sustaining the stop arranged for adjustment longitudinally of the knife to locate said stop in positions to suit heels of different heights, having provision for visually indicating the proper adjustment to suit a given height of heel.

7. A heel breasting machine, having in combination, a reciprocating breasting knife, having a constant stroke, a support for sustaining a shoe with its heel in the path of the breasting knife arranged for adjustment to bring the shoe into operative relation with the knife, means for limiting the movement of the shoe toward the knife comprising a stop arranged to be engaged by the tread surface of the heel, and adjustable means for sustaining said stop having provision for visually indicating the proper adjustment of the stop to suit a given height of heel.

8. A heel breasting machine, having in combination, a reciprocating breasting knife arranged to be driven the same distance at each stroke, a support for sustaining a shoe with its heel in the path of the breasting knife arranged for adjustment to bring the shoe into operative relation with said knife, a stop arranged to be engaged by the tread surface of the heel to limit movement of the shoe toward the knife, a supporting member provided with a guideway extending substantially parallel with the line of movement of the knife and having an opening in one of its walls, a side of said opening being

provided with a plurality of shoulders, a holder for said stop constructed for sliding movement in said guideway and having a plurality of openings respectively arranged in alignment with said shoulders, and a pin adapted to be inserted in said openings to limit movement of the stop away from the shoe support.

9. A heel breasting machine, having in combination, a breasting knife having a constant stroke, a support for sustaining a shoe with its heel in the path of the knife arranged for adjustment to bring the shoe into operative relation to the knife and a stop formed and positioned to engage the tread surface of the heel to limit movement of the shoe toward the knife, said stop being arranged for adjustment in a direction substantially parallel with the line of movement of the knife to position heels of different heights in proper relation to the breasting knife.

10. A heel breasting machine, having in combination, a breasting knife, having a constant stroke, a support for sustaining a shoe with its heel in the path of the knife arranged for adjustment to bring the shoe into operative relation to the knife and means for limiting movement of the shoe toward the knife comprising a stop arranged to be engaged by the tread surface of the heel, the said stop being sustained for angular adjustment relative to the knife whereby different heels may be breasted by cuts having different inclinations to their tread surfaces.

11. A heel breasting machine, having in combination, a breasting knife having a constant stroke, a support for sustaining a shoe with its heel in the path of the knife arranged for adjustment to bring the shoe into operative relation to the knife and means for limiting movement of the shoe toward the knife comprising a stop positioned to be engaged by the tread surface of the heel, the said stop being arranged for adjustment in a direction substantially parallel with the line of movement of the knife and for angular adjustment relative to the knife.

12. A heel breasting machine, having in combination, a breasting knife having a constant stroke, a stop arranged to be engaged by the tread surface of a heel and to be adjusted to definite, predetermined distances from the lower limit of the stroke of the knife corresponding to the standard heights of heels, a shoe support, and means for moving the same toward the knife to press the tread surface against the stop.

13. A machine of the class described, having in combination, a knife arranged to be driven the same distance at each operation, a presser foot, mechanism arranged for first resiliently depressing said presser foot and

- then starting the knife, limiting means for said presser foot arranged to limit upward movement thereof at a point in predetermined relation to the lower limit of the knife stroke, means for supporting the shoe, manually operable means for raising the shoe support to press the tread surface of the heel against said presser foot and to raise it until stopped by said limiting means. 5
- 10 14. A machine of the class described, having in combination, a reciprocating knife having a constant stroke, a movable presser foot, an adjustable means for limiting the upward movement thereof, resilient means for sustaining the presser foot against said limiting means, manually operable means for depressing said presser foot and for starting the knife, a vertically movable shoe support, a lever thereon arranged adjacent to the shoe, connections between said lever and said support for raising the shoe to clamp the same against said presser foot and for positively sustaining it against the action of the knife. 15
- 20 15. In a machine of the class described, the combination of a knife having a predetermined limit of cutting movement, a presser foot arranged to be resiliently depressed, means constructed and arranged to limit reverse movement of the presser foot at a predetermined distance from the limit of the knife, a shoe support mounted for movement transversely of the knife, a lever on said support pivoted for movement in the same plane as the support, mechanism between said lever and said support whereby the shoe is raised against the presser foot and the presser foot is forced against the stop, said mechanism being constructed and arranged 25 to positively sustain the shoe against the cutting action of the knife. 30
- 35 16. In a machine of the class described, a knife having a definite lower limit of movement, manual means adjacent the shoe for positively elevating the shoe to bring the tread surface of its heel to a predetermined distance from said limit, and means engaging the heel to receive the thrust of said elevating means. 40
- 45 17. In a machine of the class described, the combination of a tool having a fixed limit of operative movement, a presser arranged to be depressed, means to limit reverse movement of the presser at a fixed distance from the limit of the tool, a work support mounted for movement beneath said tool, a lever arranged adjacent the work and connections between the lever and the support for positively sustaining the work and 50 raising it against the presser. 55
- 60 18. A machine of the class described, having in combination, a reciprocating operating device having a definitely limited operating stroke, a movable work presser, manual means for depressing the presser upon the work and subsequently starting the machine, a work support, manual means for raising the work support to press the work against the presser and to raise the same, and means for limiting the upward movement of the presser to position the work with a portion thereof in definite relation to the limit of the operative stroke of the operating device. 70
- 75 19. A heel breasting machine having, in combination, a knife, means for actuating the knife, a shoe support mounted for movement into and out of position under the knife and for movement manually toward the knife, shoe holding means which is held depressed for contact with the heel of the shoe and is raised by the shoe in its movement toward the knife, and means for positively arresting the movement of the shoe toward the knife to determine the extent of the action of the knife upon the heel. 80
- 85 20. A heel breasting machine having, in combination, a knife, power means for operating the knife to cut the stock, a shoe support movable vertically and horizontally, manually operable means for raising the support toward the knife, yieldingly supported heel engaging means arranged for vertical movement with the support and by the shoe upon contact of the heel with said means, and adjustable stop means for limiting the upward movement of the shoe to determine the extent of the breasting cut. 90
- 95 21. A heel breasting machine having, in combination, a knife, power means for actuating the knife, a shoe support movable to position the shoe under the knife and to raise the shoe toward the knife, resiliently supported means for engaging the heel, means for raising the shoe and means whereby movement of the shoe and the heel engaging means toward the knife is adjustably limited. 100
- 105 22. A heel breasting machine having, in combination, a knife, a shoe support constructed and arranged to be brought into and out of position under the knife edge and to be raised toward the knife by the operator, yielding means in the path of the vertical movement of the support to act upon the heel in opposition to such movement and to position and hold the shoe relatively to the knife, and a fixed stop for limiting the vertical movement of the shoe. 110
- 115 23. A heel breasting machine having, in combination, a knife, a shoe support constructed and arranged to be moved into and out of position under the knife edge to position the shoe for breasting the heel and to be raised toward the knife by the operator, yielding means in the path of the vertical movement of the shoe acting upon the heel in opposition to such movement for holding the shoe relatively to the knife, and means whereby movement of the shoe 120
- 125 130

is limited to prevent cutting of the shank irrespectively of the thickness of the shank.

24. A machine of the class described, having, in combination, a knife, a shoe support, 5 movable into and out of alinement with the knife and movable vertically toward the knife, an adjustable stop for variably limiting the upward movement of the heel toward the knife, clamping means yieldingly 10 held for movement with the heel upon contact of the heel therewith, and acting to

clamp the heel throughout the movement of said means and in any position to which the said stop permits the heel to move.

In testimony whereof I have signed my 15 name to this specification in the presence of two subscribing witnesses.

WARREN FRASIER.
